UNITED STATES PATENT OFFICE.

RUSSEL B. WHITZEL, OF CINCINNATI, OHIO, ASSIGNOR TO P. WILSON & SONS,
OF SAME PLACE.

HAME.

SPECIFICATION forming part of Letters Patent No. 279,511, dated June 12, 1883.

Application filed March 26, 1883. (No model.)

To all whom it may concern:

Be it known that I, RUSSEL B. WHITZEL, a citizen of the United States, and a resident of Cincinnati, in the county of Hamilton and State of Ohio, have invented certain new and useful Improvements in Hames, of which the following is a specification.

My invention relates to improvements in that class of metallic hame-tops which are provided with loops or notches for retaining hame-straps or hame-strap loops.

It has for its object the provision of a metallic hame-top loop-strap having cast integral therewith an ornamental tip of any desired configuration, and fastening-strap loops which are united by narrow ribs or contracted webs, which, with the loops, form notches for the reception of the notch of the adjustable strap-loop, the construction being of such a nature that no coring is necessary in casting, and a light, economical, and symmetrical hame-top is obtained.

In the accompanying drawings, Figure 1 is a front elevation of a hame having my improved stop attached in place. Fig. 2 is a side or edge elevation of the same. Fig. 3 is a detail elevation of the adjustable strap-loop.

A represents the wooden hame-stock. B is a metallic strap embracing the upper and outer edge thereof, being formed so as to fit upon the end of the stock A, as shown in Fig. 1.

C C C are loops made in the metal forming strap B, through either of which loops the strap for securing the upper parts of the hames upon the collar may be passed. Loops C are cast integral with strap B, and are rigidly connected together by means of the narrow ribs or contracted webs c. Webs c materially strengthen the strap-loops C, and provide a firm bearing for a detachable strap-loop, D, used instead of the loops C or conjointly therewith. Loop D is contracted at d, so as to form a notch in the loop to closely fit in either of the notches formed between the loops C and rest upon the webs c, thereby avoiding any lateral play of the loop D when in place upon the hame.

E represents an ornamental tip or head, cast integral with the loop-strap B C, if desired.

F is an eyebolt for receiving the rein-loop f at one end, passing through the lower end of strap B and the hame-stock, to be riveted on the other side to secure one end of the said strap in place.

G is a rivet passing through the strap B on one side of the hame, thence through the hame and the end of said strap on the other side of the hame, to secure the upper part of the strap in place. Thus but two bolts or rivets are necessary to secure the top-strap attachment in place upon the hame-stock A.

The simplicity and compactness of construction and ready application of my attachment are such that a cheaper, stronger, and more symmetrical device is produced than has ever been heretofore.

I am aware that it is not new to provide a wooden hame with a metallic top piece having either notches for receiving a loose hame-strap loop or provided with raised loops for the reception of the leather hame-strap. I am also aware that an adjustable top-strap loop has been provided with a contracted extension adapted to fit on the ordinary strap-loops of wooden hames.

Having thus described my invention, what I claim is—

A top attachment for a hame, composed of a metal strap, B, having the series of strap-loops C, united by means of contracted webs c, cast integral therewith, and forming bearing-notches between the loops C, in combination with the adjustable loop D, having notch d, resting upon the webs c and fitting into the notches between the loops C, substantially as described.

In testimony whereof I have hereunto set my hand.

RUSSEL B. WHITZEL.

Witnesses:

JNO. E. JONES,
A. GLUCHOWSKY.
